UNITED STATES PATENT OFFICE.

CLARENCE E. TYLER, OF NEWARK, NEW JERSEY; FANNY J. TYLER, ADMINISTRATRIX OF SAID CLARENCE E. TYLER, DECEASED, ASSIGNOR TO S. E. T. VALVE & HYDRANT CO., A CORPORATION OF NEW YORK.

ROADWAY-BOX.

1,277,668.

Specification of Letters Patent.

Patented Sept. 3, 1918.

Application filed April 28, 1913. Serial No. 764,145.

To all whom it may concern:

Be it known that I, CLARENCE E. TYLER, a citizen of the United States, and resident of Newark, in the county of Essex and State 5 of New Jersey, have invented certain new and useful Improvements in Roadway-Boxes, of which the following is a specification.

Roadway boxes heretofore in use for giving access to the valves of the pipes or mains of a system of water distribution, which mains are located usually at fixed 10 grades under a road surface, were heretofore made of wood, concrete, reinforced 15 concrete or of metal, but in either case were difficult to assemble and to adjust to the varying depth, at which the mains were located under the road surface.

In many cases such roadway boxes were 20 made of rectangular cross section, requiring elements of construction of a variety of different patterns and provided with fastening means and interlocking means, often extending inwardly of the roadway box and 25 interfering with the ready access to the valve located at the lower end thereof.

The present invention has for its purpose 30 to provide a roadway box of circular cross section, consisting of a limited number of standard size elements, interlocked without the use of rods, bolts, etc., which elements leave the inner space of the box practically free. These elements may be so selected and arranged that a box of any 35 desired height can be constructed, according to the size of the standard elements chosen.

An additional advantage of the box consists of an adjustable top, particularly 40 adapted for use when small variations in height, such as fractions of inches, must be considered in placing the top at exactly the same level as that of the surrounding surface plan of the road.

The invention is illustrated in the accompanying drawings in which Figure 1, is an 45 elevation of the assembled roadway box, Fig. 2, a horizontal cross section in the line *a—a* of Fig. 1, Fig. 3, a central vertical cross section of the top frame and cover plate, Fig. 4, a perspective view of the top frame, and Fig. 5, a similar view of the base plate.

This new round roadway box comprises a base plate 1, in the shape of a circular frame,

which is located on top of the valve, usually 55 a gate valve, of a water main, not shown in the drawing. The plate is provided with an outer and inner annular flange 2 and 3 and a number of outer and inner upwardly extending lugs 4 and 5. The side plates 6, 7 60 and 8, are formed as parts of a cylinder and are provided with stiffening ribs 9. The interlocking means for the side plates comprise a cylindrical tongue 10 on one of the longitudinal edges of each side plate and a 65 groove 11 of circular cross section on the other of the edges. The tongue-and-groove connection between two abutting side plates forms a most efficient interlocking means, does not project into the cylindrical space 70 of the box, and, in case a plastic cement, such as asphalt should be used in the grooves, would make a substantially water proof structure.

Either or all of the side plates may be 75 provided with upwardly extending lugs 12, for the purpose of positioning an upper side plate in relation to its supporting lower side plate. As will be noted in Fig. 1, the side plates 6, 7 and 8, are of different height, and 80 in arranging the same one above the other, forming longitudinal sections of the entire cylinder, are preferably so selected, that their horizontal joints are staggered, or located in different planes, whereby a structure is produced of extreme rigidity, peculiarly adapted to resist the jars of street traffic passing over the same.

Fig. 3 illustrates the assembled cover of the roadway box which comprises the top 90 frame 13, having an outer circular flange 14, and a set of concentric inclines 15, 16, and 17. Recesses 18 on the lower edge of the frame 13, are in engagement with the lugs 12 of the upper set of side plates and 95 serve to position the frame on the plates.

The cover frame 19 is provided with a circular overhanging flange 20, entirely surrounding the flange 14 of the top frame 13 and acting as an apron to lead off the 100 rain or other water which might be capable of entering the box. A series of inclines 21, 22 and 23, are arranged on the frame and engage with the corresponding inclines 15, 16 and 17, of the top frame 13, whereby 105 the rotation of the top frame causes a vertical displacement of the same which can be efficiently utilized in the adjustment of

small differences between the level of the top of the box and that of the surrounding ground. A cover 24, closes the opening of the frame 20, giving access to the inner space 5 of the box and the valve located at the bottom thereof.

It will be noted that this round roadway box is built of longitudinal sections, each section comprising a number of superposed 10 side plates, the side plates of one section interlocked with the side plates of the abutting sections by means of a vertically extending tongue-and-groove joint. The excavation for receiving a roadway box does not 15 require to be of much larger diameter than that of the box, and the walls of the box can easily be built up in this limited space without the use of bolts, screws, tie rods, etc., an advantage which becomes of particu- 20 lar importance when the excavation is to be made through a finished roadbed, such as one of asphalt paving or Belgian paving blocks.

Claims.

- 25 1. A road box having a cylindrical side wall longitudinally and transversely divided into sections, means for interlocking the abutting sections, and a base-plate for preventing the sections from penetrating the 30 ground.
2. A road box having a cylindrical side wall longitudinally and transversely divided into sections, means for interlocking the sections so that the joints of one section are 35 broken with relation to the joints of other sections, and a base-plate for preventing the sections from entering the ground.
3. A road box having a cylindrical side wall longitudinally and transversely divided 40 into sections, tongue and groove interlocking means extending longitudinally along the sections for holding them together, lugs arranged upon the transverse edges of the sections for preventing lateral movement of

the sections, and a base-plate for preventing 45 the whole from penetrating the ground.

4. A road box having a cylindrical side wall longitudinally and transversely divided into sections, tongue and groove interlocking means extending longitudinally along the 50 sections for holding them together, lugs arranged upon the transverse edges of the sections for preventing lateral movement, and a base plate adapted to prevent the side wall from penetrating the ground. 55

5. A road box having a cylindrical side wall longitudinally and transversely divided into sections, the sections being so arranged that the joints of certain sections are broken with relation to the joints of other sections, tongue and groove interlocking means extending longitudinally along the sections for holding them together, lugs upon the transverse edges of the sections for preventing lateral movement of the sections, and means 60 for preventing the side wall from entering the ground. 65

6. A road box having a cylindrical side wall longitudinally and transversely divided into sections, the sections being so arranged 70 that the joints of certain sections are broken with relation to the joints of other sections, tongue and groove interlocking means extending longitudinally along the sections for holding them together, a base plate for preventing the side wall from entering the ground, and means upon the transverse edges of the sections and upon the base plate for preventing lateral movement of the sections. 75

In witness whereof the inventor has hereunto set his hand in the presence of two subscribing witnesses, at New York, in the county and State of New York, this 25th day of April, 1913.

CLARENCE E. TYLER.

In presence of—

RALPH JULIAN SACHERS,

M. F. KANE.
